UNITED STATES PATENT OFFICE.

GEORGE B. SMALL, OF TULSA, OKLAHOMA, ASSIGNOR OF THREE-FOURTHS TO TIDAL OIL COMPANY, OF TULSA, OKLAHOMA, A CORPORATION OF OKLAHOMA.

PNEUMATIC PUMPING APPARATUS.

Application filed October 20, 1928. Serial No. 313,773.

My invention relates to pneumatic apparatus for pumping wells and more particularly to displacement of liquid petroleum from wells with air or gas, under automatic control to supply the pressure medium when fluid has risen to a determined level in the well and discontinue the supply when the fluid has been discharged, thereby avoiding waste of the pressure medium and saving the expense of manual operation of the pumping apparatus; the present application being a continuation in part of my application Serial No. 299,923, and the invention having for its principal object to simplify control of the pressure medium by employment of differential pressures in the line through which the well is discharged in one phase of the air control.

Other objects of the invention will become apparent as disclosure of the invention proceeds.

In the accompanying drawings wherein a preferred form of my apparatus is illustrated:

Fig. 1 is a central vertical section of the apparatus and of a well to which it is applied, part of the well casing, flow line and trap being in central vertical section, the apparatus being illustrated as it appears between well flowing periods.

Fig. 2 is a similar view illustrating the parts as they appear immediately following opening of the main air valve.

Referring more in detail to the drawings: 1 designates a well hole leading through cap rock 2 and terminating in a shot hole 3 in oil sand 4. 5 designates a well casing supported on the cap rock by a shoe 6, and having a casing head 7 at the top of the well provided with a vent hole 8 for relieving pressure in the well to permit accumulation of well fluid from the sands. Extending through the casing head 7 and casing 5 is a tube 9 terminating at the bottom of the well in a trap 10 provided with a standing valve 11 and with the ordinary strainer extension 12 through which fluid in the well is led to the trap through the standing valve. The tubing is provided exteriorly of the casing head with a T-union 13, and extending through the union 13 and tube 9 is a flow line 14 through which oil displaced from the trap is delivered from the well.

The air control valve comprises a housing 15 arranged vertically on supporting legs

16, and having end chambers 17 and 18 connected by a throat 19 and closed by top and bottom plates 20 and 21 held to the body of the housing by stud bolts 22, the chambers 17 and 18 having oppositely facing valve seats 23 and 24 at the junctions of the chambers with the throat 19.

Leading from the throat 19 through the side of the housing 15 is a port 25, and threaded into said port is the reducing coupling nipple 26 of a major flow line 27, which opens into the T-union 13 for discharge through tube 9 onto oil accumulated in the trap and tube for displacing the oil through the flow line 14.

A hand valve 28 on the line 27 provides means for manual control of flow of a fluid pressure medium presently mentioned through the major flow line.

The bottom plate 21 of the housing 15 has a port 29 opening to the lower chamber 18, and threaded into said port is an elbow fitting 30 connected through a line 31 with a source of supply of fluid pressure medium such as air or gas and which may consist of a compressor indicated by the cylinder C. A hand valve 32 provides means for manually controlling flow through the line 31. 33 designates a lubricant container connected with the line 31, through which lubricant may be supplied to the line under control of the valve 34 and hand press 35.

Mounted on the top housing plate 20 is a diaphragm housing 36, including the oppositely cupped sections 37-38 having rim flanges 39-40, connected by bolts 41 and a neck 42 preferably formed integral with the lower cupped section 38 and threaded into a socket 43 in the plate 20. A flexible diaphragm 44 is clamped between the flanges 39-40 and divides the space enclosed by said sections into upper and lower chambers 45 and 46.

Extending freely from the lower chamber 18 through the throat 19 and chamber 17 and snugly through the bore of the neck 42, into the lower housing chamber 46, is a combination piston rod and valve stem 47 (hereafter referred to as a stem) having a reduced upper end 48 extended through an opening in the center of the diaphragm 44 and forming a shoulder 49. A head 50 threaded onto the upper end of said stem clamps the diaphragm to the stem. A chan-

nel 51 extending longitudinally in the stem opens laterally to the throat 19 and through a restricted orifice 52 in the reduced end of the stem into the upper diaphragm chamber 45 to provide communication between the diaphragm and vent chambers so that pressure in said chambers may be balanced under the conditions previously mentioned.

Fixed to the stem 47 is a valve 53 adapted to work in the valve chamber 18 and for cooperation with the seat 24 to control passage of air from the line 31 in major flow through throat 19 to the flow line 27. Also fixed to the stem is another valve 54 adapted to work in the vent chamber 17 and for cooperation with the seat 23 to control escape of air from the flow line and well to atmosphere through the chamber 17 and vent openings 55 in the wall of said chamber to relieve the well of pressure and permit recharging from the sands after each displacing operation. The vent openings preferably connect with a manifold chamber 56 having an outlet line 57 through which the vented air is conducted away from the apparatus and to any desired distance from the well.

Mounted on the upper diaphragm housing member 37 and communicating with the upper diaphragm chamber 45 is a T-fitting 58, having branches 59 and 60 for a purpose presently described. The head 50 of stem 47 has a greater face area than valve 53; consequently the valve, which is normally held to its seat by full line pressure, may be unseated under lower pressure on head 50.

Referring now to the means for unseating the primary piston valve to permit flow of pressure medium to the well through line 27, 61 designates a diaphragm housing including the outer and inner members 62 and 63, having the usual rim flanges connected by bolts 64 with a flexible diaphragm 65 held between the flanges and separating the interior of the housing into outer and inner chambers 66 and 67. The inner housing member 63 is provided with a neck 68 threaded onto an extension of the upper main housing head 20 to mount the diaphragm housing thereon, and including a valve chamber 69 having downwardly facing seat 70 spaced below the body of the housing member 63 to provide a throat 71. A stem 72 extends snugly through an opening 73 in the housing member 63 and carries a ball valve 74 within the chamber 69 adapted to seat on the valve seat 70. The stem also extends through the diaphragm 65 into guiding seat in a socket 75 in the outer diaphragm housing member and is fixed to the diaphragm by nuts 76 and 77 arranged on the stem at opposite sides of the diaphragm.

65 A spring 78 surrounding the stem and

bearing in a seat 79 in the inner diaphragm housing member and against the inner nut 77 normally yieldingly retains the diaphragm flexed outwardly and the valve 74 on its seat.

80 designates a connecting line leading from a port 81 opening through the neck 68 outwardly of the seat 70 to the branch 59 of the T-fitting 58 leading to the primary diaphragm piston chamber 44. 82 designates a line leading from the major flow supply line 31 to a port 83 in the neck 68 for delivering pressure medium from the line 31 to the valve chamber 69 in minor flow, a filter 84 being preferably interposed in the line 82 to restrain particles of foreign matter that might interfere with proper seating of the valve 74. Branching from the line 82 is a line 85 opening through a port 86 into the outer diaphragm housing chamber 66, and leading from said outer chamber 66 through a port 87 is a line 88 leading through the casing head of the well and through the casing exteriorly of the tubing to a point in the well adjacent the top of the trap 10. The line 88 is provided with a hand valve 89 for manual control of flow through the line and with a gauge 90 for indicating pressure in the line. An orifice valve 91 in the branch line 85 restricts flow through the branch line, thereby reducing pressure in the line 88 below that in the supply and major flow lines. Consequently the line 88 may constitute a low pressure line and the line 27 a high pressure line because of differential in pressure induced by the orifice valve.

With the parts heretofore described, automatic control of the apparatus may result from variation of conditions in the well, in that the supply of pressure medium for displacing an accumulated charge in the trap may be let into the well as follows:

Assuming that the fluid in the well is at or below the level shown in Fig. 1, then the minor flow or low pressure line 88 is exposed above the fluid in the well and pressure medium escaping through the line 82, branch 85, the outer diaphragm chamber 66 and low pressure line 88, flows freely from the open end of the line 88 and escapes through the vent 8 in the casing head, the spring 78 in the diaphragm chamber 67 retaining the diaphragm in its upwardly flexed condition and the valve 74 against its seat 70 so that none of the pressure medium is admitted through the line 80 to the top of the primary piston chamber 45.

Pressure medium admitted through the line 31 to the valve chamber 18 urges the valve 53 to its seat, shutting off flow of pressure medium to the major flow or high pressure line. When, however, fluid in the well reaches a sufficiently high level to submerge the outlet end of the minor flow line, this

line is liquid sealed and pressure of the medium admitted to the line 82, branch 85, chamber 66 and line 88 from the line 31, accumulates in these elements until it gradually 5 assumes a sufficient degree to unseat the valve 74 against the tension of the spring 78 and pressure from line 82, whereupon pressure medium is admitted through the valve seat 70, port 81 and line 80 to the top 10 of the diaphragm chamber 45 where it accumulates until, because of the differential area of the piston head 50 and valve 53, it will unseat the valve 53 to admit the pressure medium in major or high pressure flow 15 through the throat 19, coupling nipple 26 and line 27 to discharge into the trap for displacement of accumulated content of the trap.

As soon as the primary piston valve is 20 opened to admit pressure medium in major flow to the well, the supply of pressure medium to the upper portion of the diaphragm piston chamber 45 is cut off by by-passing pressure medium from the major flow line 25 back to the lower chamber 67 of the minor flow line through a line 118, preferably leading from the coupling nipple 26 through a port 119 in the lower diaphragm member 63. Cutting off supply to the top of the 30 piston chamber 45 does not interfere with the unseating of the primary valve, as pressure above and below the piston remains balanced because of the connection of the upper portion of the piston chamber with 35 the throat 19 through the channel 51 in the piston valve stem.

Attention is here called to the fact that the differential in size of the line 80 and reduced port 52 in the primary piston stem 40 will permit accumulation of the pressure medium in the piston chamber for displacing the primary piston valve, and because of differential in area of the top of piston head 50 and the face of the valve head, there will 45 be a preponderance of pressure on the piston head tending to hold the diaphragm down and the valve open, after the pressure has balanced in the chamber 45 and throat 19, resulting from communication between 50 the chamber 45 and throat 19 through the channel 51 in the piston valve stem.

When the major or high pressure line is open, content of the trap is discharged and the pressure medium would continue to flow 55 into the well unless means be provided for interrupting the flow. Such interruption of the major or high pressure flow is accomplished automatically through the following mechanism:

60 92 designates a diaphragm housing including the inner and outer members 93 and 94 having rim flanges connected by bolts 95, and an interior flexible diaphragm 96 retained by the rim flanges and dividing the 65 interior of the housing into outer and inner

chambers 97 and 98, the housing being mounted on the upper main housing plate 20 by a neck 99 containing a valve chamber 100 provided with a downwardly facing seat 101 spaced from the body of the diaphragm 70 housing to provide a throat 102. The throat 102 has an open port 103 leading to atmosphere and the chamber 100 connects with the branch 60 of the T-fitting 58 opening to the primary piston chamber 45 through a line 75 104.

Extending snugly through an opening 105 in the inner diaphragm housing member 93 into the chamber 100 is a stem 106 carrying a valve 107 adapted for seating on the seat 101 80 to close the line 104 and retain pressure medium in the primary piston chamber. The stem 106 extends through the diaphragm and is connected thereto by the outer and inner nuts 108 and 109, and is projected loosely 85 through a port 110 in the outer diaphragm housing member into a chamber 111 in an extension 112 on said housing member. A nut 113 on the outer end of the stem confines a spring 114 against the bottom of the chamber 90 111 and tends to normally yieldingly retain the valve 107 closed. A cap 115 seals the top of the chamber 111 to make the chamber air tight. Opening through the wall of the extension 112 is a port 116 for the 95 chamber 111, and leading from said port to the well discharge line or tubing 14 is a pressure line 117 through which fluid medium, which may be well fluid under force of pressure medium, may be passed from the 100 flow line into the upper diaphragm chamber to flex the diaphragm 96 and unseat the valve 107, thereby relieving the primary piston chamber to permit return of the primary piston valve to initial position. 105

Assuming the parts to be constructed and assembled as described the operation is as follows:

With the level of the liquid in the well at or below that shown in Fig. 1, the primary 110 valve will be retained closed by pressure of the fluid medium supplied from the compressor or other source, and a minor flow under low pressure will escape through the line 82, branch 85, diaphragm chamber 66, line 115 88 and the annular space between the casing and tubing of the well, to atmosphere through the vent 8 in the casing head, thereby avoiding back pressure on the sand which might interfere with flow of fluid to the well. 120

Under these conditions fluid enters the trap through the standing valve and rises in the trap, simultaneously rising in the well about the trap. When the fluid in the well reaches a level at which the outlet end of the minor flow or low pressure line is submerged, the minor flow or low pressure line is liquid sealed and pressure continuing to flow thereinto through the line 82, etc., gradually 125 builds up in the upper diaphragm chamber 130

66 until it is sufficient to displace the valve 74. When the valve 74 is displaced the pressure medium passes to the top of the piston chamber 45 through line 80 and accumulates 74 therein, the relatively small port 52 in the primary piston valve stem being insufficient 5 in size to permit escape of the pressure medium admitted to chamber 45 through the line 80 fast enough to offset accumulation in the 10 chamber.

When a sufficient amount of pressure has accumulated in the chamber 45, the dia- 75 phragm 44 is flexed and the stem 47 shifted to open the valve 53 and seat the valve 54 15 on its seat 23, thereby admitting the pressure medium to the well in major flow and under high pressure and closing the vent from the 30 throat 19.

Substantially immediately upon opening 20 of the primary valve, pressure medium is passed through the line 118 to the lower dia- 80 phragm chamber 67 to shut off flow from the line 82 to the piston chamber 45, the primary 85 valve remaining unseated because of the bal- 90 ance of pressure above and below the piston induced through the stem channel 51 and preponderance of downward pressure on the piston resulting from differential in area be- 95 tween the top of the piston head and bottom 100 of the valve head 53.

Pressure medium flowing through the line 27 under high pressure then displaces con- 105 tent of the trap through the discharge line 14.

Air for displacement of liquid from the 35 well is under pressure only slightly greater 110 than is necessary to overbalance the head of liquid in the discharge line, so that during 115 the initial period of displacement, and until 120 the trap and tube are substantially empty, 125 pressure in the flow line does not exceed about ten pounds to the square inch, which is insufficient to overcome the tension of the spring 114 which retains the vent valve 107 130 closed. When the trap is emptied, balance 135 between the head of liquid in the discharge line and the air pressure in the trap is disturbed and pressure rapidly rising in the dis- 140 charge line backs up through the line 117 145 and unseats the valve 107, thereby opening 150 the vent 101 and relieving the diaphragm 155 piston chamber 45 so that the pressure on 160 the piston is unbalanced; whereupon pres- 165 sure medium admitted through the line 31 170 reseats the valve 53 and lifts the stem 47, 175 unseating the valve 54 from its seat 23, 180 thereby opening a passage to the vents 55 185 and relieving the major flow line to elimi- 190 nate back pressure in the well that might 195 interfere with inflow of fluid from the sands. 200

The parts remain at the position last de- 205 scribed until oil again rises in the well to 210 a level for submerging the minor flow or low 215 pressure line, whereupon the cycle of opera- 220

tion is repeated for discharging a subsequent 65 charge of fluid from the well.

Thus it is apparent that the apparatus is 70 operated automatically to admit displacing medium to the well only as it is required, irrespective of the length of time it takes 75 the well to fill, and that when a charge is displaced the pressure medium is automatically shut off and admitted again only when another charge is to be removed.

It is apparent that wells equipped with 80 pumping apparatus like that described do not require manual attention except for re- 85 pairs and that the automatic control is ef- 90 fected without valves or working parts of any character within the well hole. 95

What I claim and desire to secure by Letters Patent is:

1. In combination with a well having a discharge line, a source of supply of fluid pressure medium, a piston chamber, connected valve and vent chambers having oppositely facing valve seats, a flexible dia- 100 phragm in the piston chamber, a valve in the valve chamber having a stem connected with said diaphragm, a primary conduit in- 105 cluding a section leading from said source of supply to the valve chamber, and a section leading from the valve and vent chamber connection to the well, means for conducting pressure medium from said source of supply 110 to the piston chamber, a secondary conduit connecting said source of supply with the well, means responsive to variation in pres- 115 sure in the secondary conduit induced by variation in level of liquid in the well con- 120 trolling flow of pressure medium to the piston chamber, and means responsive to change in pressure in the discharge line 125 controlling outlet of pressure medium from the piston chamber. 130

2. In combination with a well having a discharge line, a source of supply of fluid pressure medium, a piston chamber, a flex- 135 ible diaphragm in the piston chamber, connected valve and vent chambers having valve 140 seats, a valve unit including a valve located in the valve chamber and a larger area pis- 145 ton head connected with said diaphragm, a major flow conduit having a primary section 150 connecting said source of supply with the valve chamber and a section leading from the valve and vent chamber connection to the well, means for conducting pressure medium from said source of supply to the piston chamber, a secondary conduit leading 155 from said source of supply into the well, and adapted to be liquid sealed by fluid in the well, means responsive to variation in pres- 160 sure in the secondary conduit controlling flow of pressure medium to the piston cham- 165 ber, and means responsive to change in pres- 170 sure in the discharge line controlling outlet 175 of pressure medium from the piston chamber. 180

3. In combination with a well having a discharge line, a piston chamber, a flexible diaphragm in the piston chamber, connected valve and vent chambers having spaced valve seats, a valve unit including piston and main valve members of differential area located in the piston and valve chambers, connected one to the other and with the diaphragm, a valve in said unit co-operative with the seat in the vent chamber, a source of supply of fluid pressure medium having a conduit section leading to the valve chamber, whereby said main valve is normally retained on its seat by pressure of the medium supplied through said section, a conduit section communicating with the valve and vent chamber connection and leading to the well, a secondary valve chamber having a line of communication to the piston chamber, a secondary piston chamber, a piston in said secondary chamber, a valve in the secondary valve chamber connected with said secondary piston and normally closing said line of communication, means for conducting fluid pressure medium to the secondary valve chamber and to the upper portion of the secondary piston chamber, a line leading from the upper portion of the secondary piston chamber into the well and adapted for liquid sealing by fluid in the well, and pressure controlled means controlling outlet from the primary piston chamber.
4. In combination with a well having a discharge line, a piston chamber, a flexible diaphragm in the piston chamber, connected valve and vent chambers having spaced valve seats, a valve unit including piston and main valve members of differential area located in the piston and valve chambers, connected one to the other and with the diaphragm, a valve in said unit co-operative with the seat in the vent chamber, a source of supply of fluid pressure medium having a conduit section leading to the valve chamber, whereby said main valve is normally retained on its seat by pressure of the medium supplied through said section, a conduit section communicating with the valve and vent chamber connection and leading to the well, a secondary valve chamber having a line of communication to the piston chamber, a secondary piston chamber, a piston in said secondary chamber, a valve in the secondary valve chamber connected with said secondary piston and normally closing said line of communication, means for conducting fluid pressure medium to the secondary valve chamber and to the upper portion of the secondary piston chamber, a line leading from the upper portion of the secondary piston chamber into the well and adapted for liquid sealing by fluid in the well, means yieldingly urging the secondary piston to close the secondary valve, and pressure controlled means controlling outlet from the primary piston chamber.
5. In combination with a well having a discharge line, a source of supply of fluid pressure medium, a housing containing valve and vent chambers and a throat connecting said chambers having oppositely facing valve seats on its respective ends, a major pressure line having sections leading to the valve chamber from said source of supply and from said throat to the well, a diaphragm housing, a flexible diaphragm in said housing forming a piston chamber, a stem connected with said diaphragm and extending through the vent chamber and throat, having a channel opening to the piston chamber and to the throat, major line and vent valves on said stem and co-operative with said seats, a pressure line leading from said source of supply to said piston chamber, means responsive to variation in pressure in the minor pressure line controlling the line to the piston chamber, a vent for the piston chamber and means responsive to change in pressure in the discharge line controlling said vent.
6. In combination with a well having a discharge line, a source of supply of fluid pressure medium, a housing containing valve and vent chambers and a throat connecting said chambers having oppositely facing valve seats on its respective ends, a major pressure line having sections leading to the valve chamber from said source of supply and from said throat to the well, a diaphragm housing, a flexible diaphragm in said housing forming a piston chamber, a stem connected with said diaphragm and extending through the vent chamber and throat, having a channel opening to the piston chamber and to the throat, major line and vent valves on said stem and co-operative with said seats, a piston head on said stem within the piston chamber having an operative face area greater than that of the main line valve, a pressure line leading from said source of supply to said piston chamber, means responsive to variation in pressure in the minor pressure line controlling the line to the piston chamber, a vent for the piston chamber, and means responsive to change in pressure in the discharge line controlling said vent.
7. In combination with a well having a discharge line, a source of supply of fluid pressure medium, a housing containing valve and vent chambers and a throat connecting said chambers having oppositely facing valve seats on its respective ends, a major pressure line having sections leading to the valve chamber from said source of supply and from said throat to the well, a diaphragm housing, a flexible diaphragm in said housing forming a piston chamber, a stem connected with said diaphragm and extending through the vent chamber and

throat, having a channel opening to the piston chamber and to the throat, major line and vent valves on said stem and co-operative with said seats; a piston head on said stem 5 within the piston chamber having an operative face area greater than that of the main line valve, a T-fitting communicating with the piston chamber, a pressure line leading from said source of supply to one branch of

said T-fitting, a vent line leading from the other branch of said fitting, means responsive to variation in pressure in the minor pressure line controlling the line to the piston chamber, and means responsive to variation in pressure in the well discharge line controlling the vent line.

In testimony whereof I affix my signature.
GEORGE B. SMALL.
